UNITED STATES PATENT OFFICE.

HENRY C. WILLIAMSON, OF MICHIGAN CITY, INDIANA, AND CHARLES A. SCHROYER, OF CHICAGO, ILLINOIS.

CAR-AXLE-BOX LID.

SPECIFICATION forming part of Letters Patent No. 566,047, dated August 18, 1896.

Application filed October 22, 1895. Serial No. 566,673. (No model.)

To all whom it may concern:

Be it known that we, HENRY C. WILLIAMSON, residing at Michigan City, La Porte county, State of Indiana, and CHARLES A. SCHROYER, residing at Chicago, in the county of Cook and State of Illinois, citizens of the United States, have invented certain new and useful Improvements in Car-Axle-Box Lids; and we do hereby declare the following to be a full, clear, and exact description of the invention, such as will enable others skilled in the art to which it appertains to make and use the same.

This invention relates to a novel construction in a car-axle-box lid, the object being to provide an improved and more efficient device of this construction.

The invention consists in the features of construction and combinations of parts hereinabove fully described and specifically claimed.

In the accompanying drawings, illustrating our invention, Figure 1 is a vertical section of the car-axle box and lid constructed in accordance with our invention and with the lid closed. Fig. 2 is a similar view with the lid open. Fig. 3 is a cross-section taken on the line 3 3 of Fig. 1. Fig. 4 is a vertical section of a car-axle-box lid constructed in accordance with our invention and showing the lid closed, and also illustrating the manner in which the pocket 5 can be located in a different position from that shown in Fig. 1.

In car-axle-box lids it is desirable that the lid should be pivoted to the box and controlled by a spring serving not only to hold the lid closed, as shown in Fig. 1 of the drawings, but which spring will also hold the lid in an open position, as shown in Fig. 2. A construction of this kind of course is old and well known and is present in various devices of this kind, and to hold the spring to the lid, as well as to permit its ready insertion, various constructions have been proposed possessing to a certain degree objectionable characteristics, which it is the object of this invention to overcome.

In accordance with the principle involved by our invention we construct the car-axle box 1 in the usual manner—that is to say, provided with the shoulder or projection 2, to

which the lid is pivoted. The lid 3 is constructed in the usual manner, except so far as my invention applies to it, and is pivoted to the shoulder or projection 2 of the car-axle box. The plate-spring 4 is employed to hold the lid 3 firmly against the box 1, or to hold it in an elevated position, as shown in Fig. 2, and to secure this spring 4 to the lid and to permit its insertion we employ a pocket 5, which is situated on the inner face of the lid. 55 This pocket 5 is preferably cast integral with the lid and is wider at its lower end, in a direction perpendicular to the plane of the lid, than at its upper end and is transversely of a width to receive the plate-spring. Said 60 pocket 5 is provided with a shoulder 6 on the lower end of the inner face of the inner wall thereof, against which the end of the spring abuts. Between this shoulder 6 and the lid is a slot or opening 7, through which the spring 70 can pass. Adjacent to the pocket 5 and on the inner face of the lid 3 are two lugs or guides 8, between which the spring is situated, and which serve to hold the spring against lateral displacement. 75

It will be noted that the pocket or recess in the lid adapted to receive the lug or projection 2 begins where the guides 8 are situated, thus forming a bend 9 in the lid at this point, which is adapted to act as a fulcrum over 80 which the spring is bent. As the tendency of the spring is to assume its original straight form, the said fulcrum will direct its resiliency so as to hold one end of the same in engagement with the inner face of the inner 85 wall of said pocket 5 and thus prevent said end of said spring from passing over said shoulder 6.

In use, after the lid 3 has been pivoted to the projection 2 it is raised to the position 90 shown in Fig. 2. Then the plate-spring 4 is inserted through the slot 7 of the pocket 5, as shown in dotted lines in said Fig. 2, and is driven inwardly until its inner end strikes the upper face of the projection 2. Then by 95 further driving the spring the outer end thereof passes over the said upper face of the projection 2, the middle portion at this time coming in contact with said fulcrum 9, over which it is bent during its passage, to a posi- 100

tion shown in full lines in said Fig. 2, and when it reaches this position the outer end of this spring will have just passed the edge of the shoulder 6 and by its resiliency will spring 5 past the shoulder, so that it will be held firmly in position. When the spring is thus driven and the lid is in this position, the spring exerts a force to hold the lid in the elevated position; but when the lid is thrown down- 10 wardly to close the box, as shown in Fig. 1, the spring will then exert a tendency to hold the lid closed against the open end of the box, as will be plainly obvious. It will be obvious 15 that the spring may also be inserted in said pocket 5 before the lid is pivoted to the projection 2 and the spring compressed by placing its free end against said projection 2 and pressing the lid inwardly until the pivot- 20 openings therein are flush with the pivot- opening in said projection 2.

It will be seen from the foregoing description that this lid can be cast and that there are no openings through the lid, as is usual 25 in lids now commonly used, and that while the spring serves to hold the lid in the desired positions it does not project through the lid, and consequently no openings are made through which dust and dirt can enter the car-axle box. It will be seen, further, that a 30 special form of spring is unnecessary, it being sufficient to employ a straight plate-spring of a length to reach from the pocket 5 on the lid, as shown in Fig. 1, over said projection 2 to a point adjacent the end wall of the pocket 35 or recess adapted to receive said projection 2. It will be further noted that should the spring break or become useless it will never leave an opening in the lid through which dirt and dust can enter, and, further, the spring can 40 be readily replaced without removing the lid from the box.

We claim as our invention—

1. A car-axle-box lid provided on its inner face with an inwardly-extending pocket having 45 openings between the inner wall thereof and the inner face of the lid, a shoulder on the lower end of the inner face of the inner wall of said pocket, and a spring having one

end situated within said pocket and adapted to abut against said shoulder. 50

2. A car-axle-box lid provided with an inwardly-extending pocket upon its inner face and at its lower end, an opening at the upper end of said pocket, a shoulder on the lower end of the inner face of the inner wall of said 55 pocket, an opening between said shoulder and the inner face of said lid, and a spring having one end situated within said pocket and adapted to abut against said shoulder.

3. The combination with a car-axle box 60 provided with a shoulder 2, of a lid pivoted thereto, a pocket on the inner face of said lid, an opening in the upper end of said pocket, a shoulder on the lower end of the inner face of the inner wall of said pocket, an opening 65 between said shoulder and the inner face of said lid, a fulcrum on said lid, and a plate- spring having one end situated within said pocket and adapted to abut against said shoulder and bearing against said fulcrum and 70 said projection 2.

4. A car-axle-box lid provided with an inwardly-extending pocket on its inner face and adjacent to its lower end portion, an opening at the upper end of said pocket, a shoulder 75 on the lower end of the inner face of the inner wall of said pocket, an opening between said shoulder and the inner face of said lid, a fulcrum on said lid, guide-lugs adjacent said fulcrum, and a spring having one end 80 situated within said pocket and adapted to abut against said shoulder, said spring passing over said fulcrum and between said guide-lugs.

In testimony whereof we affix our signatures in presence of two witnesses. 85
